UNITED STATES PATENT OFFICE.

OTTO BANNER, OF EASTON, PENNSYLVANIA, ASSIGNOR TO INGERSOLL-RAND COMPANY, OF JERSEY CITY, NEW JERSEY, A CORPORATION OF NEW JERSEY.

CENTRIFUGAL COMPRESSOR.

1,110,864.

Specification of Letters Patent. Patented Sept. 15, 1914.

Application filed October 25, 1912. Serial No. 727,650.

To all whom it may concern:

Be it known that I, OTTO BANNER, a subject of the German Emperor, residing at Easton, in the county of Northampton and 5 State of Pennsylvania, have invented a certain new and useful Improvement in Centrifugal Compressors, of which the following is a specification.

This invention relates to centrifugal compressors and more particularly to the regulation of such compressors.

When centrifugal compressors are designed for supplying different volumes of air or other fluid at a constant pressure 10 15 their capacity can be varied within quite large limits simply by regulating the motor by ordinary speed governing means. There is a limit however to this regulation since if the output of the compressor is decreased to 20 less than a certain percentage of its full load (say 50 or 60% according to the design) the compressor will "pump," that is, instead of the air or gas flowing continuously through the compressor, it will build up 25 pressure at certain points which will overcome the air currents coming through and force its way back through the impellers causing a pulsation or pumping effect in the compressor.

30 Various means have been proposed for obviating this difficulty such for instance as allowing sufficient quantity of air to pass through the compressor to prevent pumping but permitting any excess over the amount 35 desired in the load line to escape to the atmosphere. All these methods however result in the waste of the considerable power required to force this excess air through the compressor.

40 The object of the present invention is to provide means whereby a regulation below the pumping limit can be effected and yet there will be only a small proportion of power wasted.

45 With this object in view I have devised a compressor and a regulation means therefor, a practical embodiment of which is shown in the accompanying drawings in which—

50 Figure 1 is a side elevation partly in section of the compressor and the regulating means. Fig. 2 is a horizontal section on the line 2—2 of Fig. 1 showing a detail of the regulating means.

55 In the drawings the compressor proper is shown as comprising a casing 1 in which

rotates a shaft 2 provided with a series of impellers 3 to which air or other gas from the inlet 4 is successively passed and is discharged into the exhaust pipe 5. Mounted on the shaft 2 is a turbine wheel 6 provided 60 on its outer periphery with blades 7. This turbine wheel is adapted to be actuated under certain conditions by air or gas taken from the discharge pipe 5 through a pipe 8 and delivered to the blades of the turbine 65 wheel through nozzles 9, 10, 11, 12, 13 by a regulating mechanism which will now be described.

The air or gas passing from the discharge of the compressor is carried through a measuring device, here shown, as a Venturi tube 14 of ordinary construction which, as is well known, gives a difference in pressure between its throat 15 and its discharge opening 16 varying with the amount of air passing through it. From these points, namely the throat 15 and the discharge opening 16, pipes 17 and 18 respectively lead to the upper and lower ends of a cylinder 19 in which is reciprocally mounted a piston 20. A 70 spring 21 tends to move the piston 20 in a downward direction and is of such a strength that the position of the piston varies with the difference of pressure in the ends of the cylinder caused by the difference 75 in pressure in the throat and discharge opening of the Venturi tube 14.

A rod 22 is secured at the lower side of the piston and operates through a connecting arm 23, a cam rod 24 on which is secured a series of cams 25, 26, 27, 28, 29. These cams co-act with plates 30, 31, 32, 33, 34 secured by rods 35, 36, 37, 38, 39 to valves 40, 41, 42, 43, 44 which are slidably mounted 80 in the side of a valve chest 45 and control 85 respectively the nozzles 9, 10, 11, 12, 13. Springs 46, 47, 48, 49, 50 surrounding the valve rods and engaging the plates 30, 31, 32, 33, 34 tend to hold the valves in open 90 position.

100 In operation, regulation above the pumping limit is effected as previously stated by ordinary speed governing means. When the compressor is operating above this limit the difference in pressure in the throat 15 and the discharge 16 of the Venturi tube 14 is such that the piston 20 is held in its uppermost position and the cams 25 to 29 are consequently in such a position that the valves 40 to 44 are pressed inwardly closing the 105 110

nozzles 9 to 13 and allowing no air to pass through the pipe 8. The spring 21 however is of such a strength that as soon as the amount delivered by the compressor falls to 5 the point where pumping begins it will move the piston 20 downward, the difference in pressure in the ends of the cylinder not being sufficient to counteract its influence. This downward movement will first cause 10 the face of the cam 37 to recede allowing the valve 44 to open slightly which will permit air from the discharge pipe 5 to pass through the pipe 9 and through the nozzle 13 to the blade 7 of the turbine wheel 6. This of 15 course will exert a rotative force on the shaft 2 and will relieve the motor driving the compressor of a certain amount of load. If the demand on the compressor falls still lower the piston 20 will move further downward 20 allowing valves 43, 42, 41, 40 to open successively, the number opening depending upon the amount of air demanded. In this way a successively greater amount of air will be withdrawn from the discharge pipe 5 and 25 passed through the nozzles to the turbine wheel increasing the amount of power developed by the wheel and relieving to a proportionate extent the load on the motor driving the compressor. In this way when the 30 demand is low instead of a constant amount of power being required below a certain limit by reason of the fact that all excess over the demand below the pumping limit is wasted, the power expended will bear a ratio to the 35 demand depending on the efficiency of the turbine wheel and will be accordingly reduced when the compressor is running under the pumping limit.

The arrangement as shown is only one of a 40 number of modifications which might be devised. Any form of measuring device could be substituted for the Venturi tube shown and any form of throttling mechanism whether with a plurality of nozzles or not, 45 could be used instead of the arrangement shown. Furthermore, the air turbine wheel may have any number of rows of blades or stages and may or may not be directly connected with the compressor shaft. It is ad- 50 vantageous however to have the discharge from the turbine wheel led to the compressor impellers as the expansion through the turbine reduces the temperature of the air or gas to a lower degree.

55 In some cases, for instance in high pressure compressors, the expansion of the air may reduce the temperature of the compressor to such an extent that the circulation water would freeze. Under such conditions 60 the air from the discharge may be heated to the desired extent by any suitable means, such as a steam jacket 51 before being conveyed to the expansion nozzles of the turbine wheel.

65 It is to be understood that the present

showing and description discloses only one specified modification of my invention and other forms and modifications are included in the spirit and scope of the invention as expressed in the claims.

70

What I claim is:

1. In combination a centrifugal compressor having a discharge line, a demand measuring device, an engine operated by compressed fluid from said discharge line, 75 and means controlled by said demand measuring device to supply fluid to said engine from said discharge line in an amount in- versely proportionate to the demand.

2. In combination a centrifugal compressor having a discharge line, a demand measuring device, an engine operated by compressed fluid from said discharge line and operatively connected with said compressor, and valve mechanism operated from 85 said demand measuring device to supply fluid from said discharge line to said engine in an amount inversely proportionate to the demand.

3. In combination, a centrifugal compressor having a discharge line, a demand measuring device in said discharge line sup- 90 plying two fluid pressures whose difference varies with the demand, an engine operated by fluid from said discharge line and op- 95 eratively connected with said compressor, valve mechanism for controlling the flow of fluid from said discharge line to said engine, valve motor mechanism for controlling said valve, and fluid connections for conveying 100 the two pressures from said demand meas- 105 uring device to said valve motor mechanism for operating said valve motor mechanism.

4. In combination, a centrifugal com- 110 pressor, having a discharge line, a Venturi tube in said discharge line, an engine op- 115 erated by fluid from said discharge line, and operatively connected with said com- 120 pressor, valve mechanism for controlling the flow of fluid from said discharge line to said engine, a valve motor comprising a cylinder and piston for operating said valve, and fluid passages leading from the throat and discharge of said Venturi tube to opposite 125 ends of said cylinder to move said motor pis- 130 ton as the discharge through said Venturi tube varies.

5. In combination a centrifugal com- 130 pressor having a discharge line, a demand measuring device, an engine operated by compressed fluid from said discharge line, 135 means controlled by said demand measuring device to supply fluid to said engine from said discharge line in an amount in- 140 versely proportionate to the demand and means to heat said fluid before it is admitted to said engine.

6. In combination, a centrifugal com- 145 pressor having a discharge line, a demand measuring device, an engine operated by

compressed fluid from said discharge line, means controlled by said demand measuring device to supply fluid to said engine from said discharge line when said demand falls below a predetermined minimum and means to heat said fluid before it is admitted to said engine.

7. In combination, a centrifugal compressor having a discharge line and a demand measuring device, an engine operated by compressed fluid from said discharge line, and means controlled by said demand measuring device to convey fluid to said engine from said discharge line when said demand falls below a predetermined minimum.

8. In combination, a centrifugal compressor having a discharge line, a demand measuring device in said discharge line, an engine, a passage for conveying operating fluid from said discharge line to said engine, a valve mechanism in said fluid passage for

controlling the flow therethrough, and operative connections between said valve mechanism and said demand measuring device to admit fluid to said engine when the demand falls below a predetermined minimum in an amount proportionate to the fall of the demand below said predetermined minimum.

9. In combination, a centrifugal compressor having a discharge line and a demand measuring device, an engine, means controlled by said demand-measuring device to convey fluid from said discharge line to said engine when the demand falls below a predetermined minimum and means for heating the fluid conveyed to said engine.

In testimony whereof, I have hereunto set my hand.

OTTO BANNER.
